(57) **CLAIM**

The ornamental design for safety razor, as shown and described.

DESCRIPTION

FIG. 1 is a perspective view of a safety razor of the present invention;

FIG. 2 is a front view thereof, the rear view being a mirror image of FIG. 2;

FIG. 3 is a top plan view thereof;

FIG. 4 is a bottom plan view thereof;

FIG. 5 is a right side view thereof;

FIG. 6 is a left side view thereof;

FIG. 7 is an enlarged cross-sectional view taken along line 7—7 of FIG. 3;

FIG. 8 is a front view of the safety razor with a cap; and, FIG. 9 is a left side view of the safety razor with a cap.

The broken lines in FIGS. 8 and 9 are shown for illustrative purposes only and form no part of the claimed design.
